UNITED STATES PATENT OFFICE.

MARTIN E. DOWNEY, OF BOSTON, MASSACHUSETTS.

COVER-LIFTER FOR OIL-CAN NOZZLES.

1,196,217.

Specification of Letters Patent. Patented Aug. 29, 1916.

Application filed January 18, 1916. Serial No. 72,836.

To all whom it may concern:

Be it known that I, MARTIN E. DOWNEY, a citizen of the United States, residing at Boston, in the county of Suffolk and State of Massachusetts, have invented new and useful Improvements in Cover-Lifters for Oil-Can Nozzles, of which the following is a specification.

This invention relates to oil cans having elongated nozzles, such as are used in injecting oil into oil cups connected with shaft bearings, the oil being usually forced from the can by flexure of the bottom thereof.

The invention has for its object to provide an oil can nozzle with a device whereby the spring-closed cover of an oil cup may be engaged in such manner that by suitably manipulating the can and nozzle the cover may be conveniently lifted from its seat and held in position to permit the injection of oil into the cup.

The invention consists in the improvements which I will now proceed to describe and claim.

Of the accompanying drawings forming a part of this specification: Figure 1 represents a perspective view of a cover-lifter embodying my invention, formed as an attachment adapted to be detachably engaged with an oil can nozzle; Fig. 2 represents a perspective view of an oil can equipped with said attachment; Figs. 3 and 4 represent side elevations, each showing a portion of a nozzle, a lifter thereon, an oil cup, and the cover thereof, said views illustrating the manipulation of the nozzle causing the lifting of the cover; Fig. 5 represents a side view illustrating a modification.

The same reference characters indicate the same or similar parts in all the views.

In the drawings, 12 represents the body and 13 the tapering nozzle of an ordinary oil can.

14 represents a fixed oil cup, which may be attached to a shaft bearing (not shown) in any suitable way, and is provided with a cover 15, which is normally held closed on the mouth of the cup by a spring 16, as shown by Fig. 3, the edge of the cover overhanging the outer side of the cup.

In carrying out my invention I provide the nozzle 13 with a cover lifter which includes an elongated piece or body 17 preferably of sheet metal, secured to the nozzle, with the outer end of the lifter projecting forward from the outlet end of the nozzle,

and at one side of said end, the relative arrangement of the nozzle and the lifter 17 being such that the operator may engage the outer end of the lifter with the overhanging edge of the cover, as shown by Fig. 3, and then lift the cover by swinging the nozzle and lifter upwardly, and at the same time moving the nozzle and lifter endwise, as shown by Fig. 4, until the outlet end of the nozzle projects under the lifter cover. The cover-engaging surface of the lifter is located wholly at one side of the nozzle and is unobstructed, so that it is movable into the space between the mouth of the cup and the displaced cap far enough to permit the outlet end of the nozzle to also enter said space, as shown by Fig. 4.

The outer end of the lifter 17 is considerably wider than the diameter of the outlet end of the nozzle, so that it is adapted to engage and lift the cover without liability of slipping out of engagement with the cover during the operation. It is difficult to lift the cover of an oil cup by directly applying the outlet end of the nozzle thereto, particularly when the cup is in a relatively inaccessible location, because the nozzle is liable to slip out of engagement with the cover. This difficulty is obviated by the employment of the lifter arranged as shown.

I also provide the nozzle with a stop member 19, which projects from one side of the nozzle behind its outlet end, and is arranged to bear on the outer side of the cup 14, as shown by Fig. 4, when the outlet end is in position to inject oil into the cup, provision being thus made for accurately locating the nozzle in operative relation to the cup.

I prefer to construct the lifter and the stop member 19 as an attachment adapted to be detachably applied to the nozzle, the stop member being carried by the lifter.

As here shown, the stop member is an ear integral with the sheet metal body of the lifter and bent therefrom, as indicated by Fig. 1, the said ear being provided with an orifice 20 formed to receive the outer end portion of the tapered nozzle and come to a bearing thereon when the outer end of the lifter is in advance of the outlet end of the nozzle and the ear or stop member is behind said outlet end.

The inner end portion of the lifter is preferably provided with a socket 21 formed to embrace the nozzle and additionally secure the lifter thereto.

The lifter may be curved to conform to a curved nozzle, as shown by Fig. 5.

Having described my invention, I claim:

1. A cover-lifter adapted to be attached 5 to an oil can nozzle and arranged to project forward from the outlet end of the nozzle and at one side of said end, said lifter having an unobstructed cover-engaging surface permitting the insertion of the lifter 10 and the nozzle end into the space between an oil cup mouth and a cover displaced by the lifter.
2. A cover-lifter having nozzle-engaging means and arranged relatively to said means 15 to project forward from the outlet end of a nozzle engaged thereby, said means including a stop member arranged to project from one side of the nozzle behind its outlet end, and to bear on the outer side of an oil cup.
- 20 3. A cover-lifter comprising an elongated

body portion having a laterally projecting ear spaced from its outer end, and formed to receive an oil can nozzle, said ear being adapted to bear as a stop member on the outer side of an oil cup, and to locate the 25 outer end of said body portion in advance of the delivering end of the nozzle.

4. A cover-lifter comprising an elongated body portion having a socket at its inner end portion adapted to embrace an oil can 30 nozzle, and a laterally projecting ear spaced from its outer end, and formed to receive the said nozzle, said ear being adapted to bear as a stop member on the outer side of an oil cup, and to locate the outer end of 35 said body portion in advance of the delivering end of the nozzle.

In testimony whereof I have affixed my signature.

MARTIN E. DOWNEY.
